UNITED STATES PATENT OFFICE.

NATHANIEL LOMBARD, OF WORCESTER, AND WALTER E. LOMBARD, OF ARLINGTON,
MASSACHUSETTS.

RAILWAY-SIGNAL-RECORDING DEVICE.

1,158,821.

Specification of Letters Patent.

Patented Nov. 2, 1915.

Application filed February 8, 1904, Serial No. 192,648. Renewed April 3, 1915. Serial No. 19,057.

To all whom it may concern:

Be it known that we, NATHANIEL LOMBARD and WALTER E. LOMBARD, citizens of the United States of America, and residents, respectively, of Worcester, county of Worcester, and Arlington, county of Middlesex, both in the State of Massachusetts, have invented certain new and useful Improvements in Railway-Signal-Recording Devices, of which the following is a specification.

This invention relates to devices for the regulation of the movement of trains and has for its object the production of a system whereby a record is obtained of the exact time of the operation of each movable member assisting in the regulation of said train movement, such record being made at the place of operation and a duplicate record being made in a central station.

It further consists in recording the exact time a train passes each movable member and it consists mainly in a recording device comprising in part a record member having imprinted thereon suitable marks designating periods of time co-acting with two record-producing members, one of which is actuated by the passing of a train and the other of which is actuated by the operation of said movable member.

The aim of the invention is to produce a record showing the exact point any switch, signal, or other danger-warning device may be at the time of the passage of a train. Heretofore, in block systems, danger signals have been exposed to view to indicate to the engine driver that there is danger ahead and that the train should not enter upon said block until the signal was again operated to show that the tracks were clear. Often times accidents have happened and testimony of the engine drivers, firemen, and other train hands responsible for the accident, has been that the danger signal was not exposed and that the signal was in a position to indicate a clear track and heretofore it has often been impossible to controvert this testimony. To obviate this difficulty and produce a positive record which will show conclusively the exact position any

switch, signal, drawbridge, or other movable member adapted to regulate the movement of trains at the time of the passing of a train is the object of this invention, and it consists in certain novel features of construction and arrangements of parts which

will be readily understood by reference to the description of the drawings and to the claims to be hereinafter given.

Of the drawings: Figure 1 represents a sectional view of a recording device embodying the features of this invention. Fig. 2 represents a sectional elevation of the same. Fig. 3 represents an elevation of a semaphore showing the contact devices therefor. Fig. 4 represents a section of a rail showing the contact devices therefor adapted to be operated by a passing train. Figs. 5 and 6 represent details of the record strip, and Figs. 7, 8 and 9 represent, respectively, diagrams of the clock-controlling mechanism, the passing-train-recording mechanism, and the semaphore-recording mechanism.

Similar characters designate like parts throughout the several figures of the drawings.

In the drawings, 10 represents a rail of an ordinary railroad, adjacent to which are a plurality of semaphores 11 distributed along the road at predetermined intervals. The semaphore 11 is operated by the ordinary actuator 12. In the present system the actuating rod 12 passes through a chamber 13 in the recording box 14 secured to the post 15 of said semaphores. The rod 12 has secured thereto an arm 16 adapted to operate a contact 17 mounted within the chamber 13 so that when the semaphore has been moved into a danger-warning position the contact 17 will make an electrical connection in the circuit 18. In the circuit 18 is a battery 19 and a magnet 20 located within the recording box 14.

The magnet 20 operates an armature 21 pivoted at 22 and provided with an indenting device 23 in its free end, a spring 24 maintaining the armature 21 free from the magnet 20 in its normal position with the indenting device 23 removed from the record strip 25 passing over a drum 26.

The drum 26 is operated by any suitable clock mechanism 27, the casing alone of which is shown in the drawings. The record strip 25 is mounted on a spool 28 revolvable with a shaft 29 mounted in bearings in the stand 30. The shaft 29 has secured thereon a brake-drum 31 which co-acts with a brake-band 32 adjustably secured to the stand 30 to prevent the record strip from being unwound from the spool 28 except as said strip is operated by the clock

mechanism 27. The drum 26 is provided with a series of projections 33 radiating therefrom and registering with perforations 34 in said record strip to insure a positive movement of said strip with said drum 26 to move the same positively at a uniform speed beneath the record-producing members 23.

The record strip is wound up on a spool 35 mounted in bearings on the stand 36. The spool 35 is operated by means of a drum 37 co-acting with that portion of the strip 25 wound on said spool 35 said drum 37 being mounted in a lever 38 pivoted on the shaft 39 of the clock mechanism 27, said shaft 39 having secured thereon a gear 40 meshing with an intermediate gear 41 which in turn meshes with a gear 42 secured to the drum 37 and by which said drum is operated by the clock mechanism to wind up the strip 25 upon the spool 35 as fast as it passes from the drum 26.

The drum 37 is kept in contact with the strip 25 wound up on the spool 35 by means of a weight 43 on the lever 38. To the rail 10 is secured a contact device 44 which is operated by the wheels of a passing train to complete the circuit 45 in which a battery 46 and a magnet 47 operates an armature 48 pivoted at 49 to cause a recording pen 50 to indicate upon the record strip 25 the time and length of duration of the passing of each train that passes along the rail 10. The wheels of said passing train operate the contact device 44 to cause the pen 50 to make a series of dots or dashes on the strip 25, said dots or dashes indicating the nature or species of the train passing and the duration of passing. For instance, if an express train passes, the train passing over the contact device 44 at a rapid rate would indicate upon the strip 25 a series of dots close together, each dot representing a wheel of the train passing. The number of dots upon the line would indicate the number of wheels passing over the rail and the length of the dots indicated on said strip would indicate the time it took said train to pass (see Fig. 5). The rate of speed of an accommodation train 50 would be much slower and as a consequence the marks made by the passing train would be short dashes and the length of the line on said strip would be greater for the same number of cars, substantially as indicated at the right of Fig. 6. A freight train passing would move so much more slowly that the marks made by the record-producing device would be in the nature of long dashes as indicated at the left of Fig. 6. It is obvious therefore that in this device the record-producing device will indicate upon the record strip the nature or species of every train that passes a given point.

The record strip 25 has imprinted thereon 65 suitable marks designating the periods of

time, such as days, hours, minutes and parts of minutes, as shown in Figs. 5 and 6, and the strip 25 must be operated by the clock mechanism 27 so that at a given time, say 10.40 a. m., January 1, 1901, the mark on 70 said strip indicating that exact time would be immediately beneath the record-producing devices, so that if, at that exact time, a train passes over the rail 10 the record-producing device 50 would operate to mark 75 upon said strip that at that time a train commenced to pass over the rail 10.

The record strip 25 must move beneath the record-producing device with the same speed as the regulating clock 51 in the central station 52 so that in one hour's time there will pass beneath said record-producing device as much of said strip 25 as has imprinted thereon the divisions of time equal to one hour. This being the case, a record is 85 made upon the strip 25 not only of the time when the train commenced to pass over the contact device 44 but also records the exact time when the last truck passed over said contact device. 90

It will therefore be seen from the foregoing that not only is the exact time of the passing of a train marked upon said record strip 25 but the exact time that the signal or other device operates is also marked upon 95 said strip 25 so that at any time should occasion require, this strip would testify as to the fact of the exact position of any warning signal when the train passed said signal or other warning device. If, for instance, the 100 danger signal was down, which should be a warning for an engine driver to stop and not pass the danger point and said engine driver should ignore this warning signal and pass the signal when the danger signal was 105 down, a record of this fact would be indicated upon this strip inasmuch as the markings on said strip for the operation of the train and the signal would overlap each other. Should, however, the danger signal 110 be up and give no warning signal to an engine driver, and he should pass the danger signal and immediately thereupon while the train was still passing, the danger signal would operate, this fact would be indicated 115 upon the strip and thereby relieve the engine driver from any responsibility for accidents which might occur.

In order to prevent the destruction of evidence in case an accident should occur by destroying the recording system at the point of operation of a signal or other device, a duplicate recording system for each signal or other danger-warning device is installed at a central station and the same record is 120 kept on this recording mechanism as is kept on the record member attached to said semaphore, so that in case one of the recording mechanisms should be detached the duplicate record at a point considerably removed from 125 130

said signal would still be in evidence. Moreover, at the central station, by having a duplicate recording mechanism for each semaphore or other device for the regulation 5 of the movement of trains an operator stationed therein could readily keep tabs on the movement of all trains along the line, regulating to better advantage the movement of these trains by informing the engine drivers when it was safe to make better time and when they should decrease their speed.

Having thus described our invention, we claim:

1. Means for automatically recording the 15 operations of a device for regulating the movements of trains, associated with means for automatically recording the passage of trains by a chosen point in proximity to the said regulating device, the recording device 20 or devices being of such a character as to show the time relationship of the respective acts thus recorded.

2. The combination with a railway signal 25 adapted to control the movement of trains, of two recording devices, two record member supporting elements; a single mechanism for continuously operating said record supporting elements in unison; and means operated by said signal for simultaneously producing the same record by each of said recording devices on each of said record members.

3. The combination with a railway signal 35 adapted to control the movement of trains, of two revolute spools for supporting a record strip, a revolute drum over which said strip passes interposed between said

spools, clock mechanism for operating one of said spools, a device for producing a record upon said strip, means actuated by the movement of the signal for operating said record-producing device, and means for recording upon said strip the time a train passes.

4. The combination with a railway signal 45 adapted to control the movement of trains, of two revolute spools for supporting a record strip, a revolute drum over which said strip is adapted to pass interposed between said spools, a device for producing a record upon said strip, a pressure roller bearing upon the surface of said strip, and clock mechanism for operating said roller to revolve said spools and wind up the strip 50 thereon.

5. The combination with a railway signal adapted to control the movement of trains, 55 of two revolute spools for supporting a record strip, a revolute drum over which said strip is adapted to pass interposed between said spools, means for revolving one spool to wind up said strip, a brake upon the other spool to prevent too rapid unwinding of the strip thereon, a device for producing a record upon said strip, and means actuated by the movement of the signal for operating said record-producing device.

Signed by us at Boston, Massachusetts, this 27th day of January, 1904.
